UNITED STATES PATENT OFFICE.

FRED LEE, OF COVENTRY, ENGLAND.

PIVOT.

1,331,113.

Specification of Letters Patent.

Patented Feb. 17, 1920.

Application filed May 31, 1917. Serial No. 171,946.

To all whom it may concern:

Be it known that I, FRED LEE, a subject of the King of England, residing at Coventry, Warwickshire, England, have invented certain new and useful Improvements in Pivots, of which the following is a specification.

This invention relates to the pivoting of instruments and more especially instruments exposed to vibration, such for example as compasses employed on aircraft, in which position they are subjected to exceptional vibration. The invention is, however, applicable to a variety of other instruments which are subject to vibration, for example instruments in which steel, iridium, or other metallic pivot points are employed. Considerable difficulty has arisen in connection with the pivoting of compasses for use on aeroplanes, in which steel, and subsequently iridium, pivot points of the well-known kind have been employed working in a stone cup or bearing. The vibrations of the aircraft are found to affect the working of these metal pivots and stone bearings, so that the results are unsatisfactory after a brief period of use. The point of the pivot and the stone bearing are found to be very rapidly destroyed by the vibration set up, and consequently the compass loses its sensitivity. With steel pivots which have been most usually employed working in a stone cup under such conditions, cutting is found to occur rapidly and iridium pivot pins have given but little better success. It is the object of the present invention to overcome this difficulty.

According to this invention, in instruments subject to vibration there is employed a pivot and a bearing therefor, for example a cup, both of stone, such as is used for jeweled bearings, characterized by the polish of the rubbing-surfaces being such that no roughness is visible under a magnification of not less than 25 diameters. The stone is such as is used for jeweled bearings to prevent deformation, such as sapphire, agate, ruby, or diamond, or any of the precious or other stones, including synthetic stones, which are sufficiently hard to provide a good durable point and to take the requisite polish, without being so hard as to be unworkable.

The shape of the pivot is preferably that of a cone, the angle at whose apex lies between 56° and 70° , and of which about two-

thousandths of an inch at the apex have been rounded off, the side of the cone being very slightly bulged so as to be in the form of a parabola instead of straight, whereby any tendency to crack is prevented. The choice of angle between the above limits depends upon the question whether sensitivity or durability is more important: for durability the blunter angle is to be preferred. 60

One form of pivot point and cup for use in an instrument subject to vibration, according to this invention, will now be described with reference to the accompanying drawing which shows a much enlarged view 70 of the pivot and cup. A is the pivot of agate having an angle at its apex of between 56° and 70° , and slightly blunt by having about two-thousandths of an inch at the apex rounded off. The side of the conical-shaped point is bulged slightly so as to be in the form of a parabola. The pivot is carried in the end of a support B of brass or other material which is drilled to receive it, and works in the cup C of sapphire. The 80 rubbing surfaces of the pivot point and the cup are polished to a much higher degree than has heretofore been the practice, namely, so that when examined under a microscope and magnified to not less than 25 85 diameters, no pits or excrescences can be seen. The cup is of such curvature that the pivot will work smoothly in it and permit the tilting of the pivot when necessary.

In many cases the pivot point is carried 90 in a hole drilled in one end of a brass pillar which is provided at the other end with a screw by which it is secured to the bottom of the compass case. The cup is arranged to ride on the pin. 95

Any form of mounting may be employed that is desirable and appropriate to the work in hand, and the pivot point and cup according to the present invention, may be employed not only in compasses but in any 100 kind of instrument subject to vibration for which it is suitable or desirable.

The pivot may be either stationary or rotating.

I have found sapphires to be suitable for 105 this work, but of the sapphires obtainable from Cashmere, Ceylon, Montana and Australia, I have found the last mentioned used as pivot points to work satisfactorily in cups formed from Montana sapphires. 110

When agate is employed for the pivot points, care must be taken to use only sam-

ples of the stone which are free from definite crystalline structure, and it has been found that smoky agate having an amorphous structure is most suitable, and the banded 5 variety should not be used.

It is to be understood that this invention is not limited to the use of any particular stones, but consists in the employment of stone pivot points and stone cups in instruments subject to vibration, such as compasses, and in affording the rubbing surfaces of the pivot point and the cup a very high degree of polish whereby they work sweetly, even though subjected to vibration, 10 without cutting.

It has been proposed to employ in watch-work a staff having jewel pivots working in jewel holes with end-stones, and no claim is made for such construction in the present 15 specification.

What I claim as my invention and desire to secure by Letters Patent is:—

1. In an instrument bearing the combination of a conoidal pivot, the angle at the 20 apex being between 56° to 70° and having about two-thousandths of an inch at the apex rounded off, and a cup-bearing therefor both said parts being formed of stone,

such as is used for jeweled bearings, but having the rubbing surfaces polished to such 30 a degree that roughness, if any is present, is only visible under a microscopic magnification of twenty-five diameters, or more.

2. In an instrument bearing the combination of a conoidal pivot the angle at the 35 apex being between 56° to 70° and having about two-thousandths of an inch at the apex rounded off, the side of the cone being slightly bulged so as to be in the form of a parabola, instead of straight, whereby the 40 tendency to cracking is prevented, and a cup bearing therefor both said parts being formed of stone, such as is used for jeweled bearings, but having the rubbing surfaces 45 polished to such a degree that roughness, if any is present, is only visible under a microscopic magnification of twenty-five diameters, or more.

In testimony whereof I have signed my name to this specification in the presence of 50 two subscribing witnesses.

FRED LEE.
